UNITED STATES PATENT OFFICE.

HENRY C. NEUBERGER, OF NEW YORK, N. Y., ASSIGNOR TO CONCRETE METAL MOLDS COMPANY, OF CARLISLE, PENNSYLVANIA, A CORPORATION OF DELAWARE.

MOLD PARTITION.

Application filed September 10, 1923. Serial No. 661,843.

This invention is directed to a novel and unique form of partition adapted to be used in cement molding machines and more especially those machines adapted for the casting or molding of building blocks. The machines in which the invention is adapted for use may be the well known gang molds wherein several blocks are molded at one time or an apparatus of the character described and claimed in my copending application filed on even date herewith and wherein two blocks at a time are adapted to be cast. In either case, the partition is employed to divide the main mold chamber of the apparatus or machine into a plurality of mold cavities in each of which a block is cast.

The invention is intended primarily to cast a block described and claimed in my application on building block filed on even date herewith and will be described in this use.

It has been heretofore common to use partitions to divide the main mold chamber into smaller mold cavities, but in all of these prior devices the partitions have been so formed that the resulting blocks are limited in their uses.

The partition of this invention is so constructed in contradistinction that it is adapted to cast a block adapted for general application, not restricted to use in a running wall but adapted to be employed for return corners, pilasters, pillars, columns, etc.

In its preferred practical form, the partition of the present invention is constructed from sheet or cast metal and its opposite sides are complementary to one another with its longitudinal cross section a duplication of its transverse cross section both in shape and proportions. This shaping and proportioning of the partition imparts to it the function stated, namely, its ability to mold a block adapted for substantially universal use.

Features of the invention, other than those adverted to, will be apparent from the hereinafter detailed description and claims, when read in conjunction with the accompanying drawings.

The accompanying drawings illustrate different practical embodiments of the invention, but the constructions therein shown are to be understood as illustrative, only, and

not as defining the limits of the invention.

Figure 1 is a perspective view of the partition embodying the present invention.

Figure 2 is a longitudinal section on the line 2-2 of Figure 1.

Figure 3 is a section of three blocks such as would be cast between two such partitions as shown in Figure 1. In Figure 3, one of the blocks is shown in complete section, while the other two are shown in fragmental section.

Figure 4 is a perspective view of a cored partition; and,

Figure 5 is a section of a cored block resulting from the use of partitions such as shown in Figure 4.

Referring first to Figures 1-3, the partition is shown as constructed from sheet or cast metal, preferably cast iron, the partition being so made that its opposite faces are complementary to one another whereby one of its faces 1 is adapted to cast the female face of a block while its other face 2 is adapted to cast the male face of another block. The partition is so configurated that its longitudinal section is in the form of multiples of its transverse section and in the showing of the drawings, the partition is twice as long as it is high and its longitudinal section is therefore equal to two transverse sections of the partitions. That is to say, that portion of the partition to the left of the center line 3 in Figure 2 is identical with that portion of the partition to the right of said center line, while each is identical with the transverse section of the partition. In this is the underlying feature of the present invention.

In Figure 3, three blocks cast individually between two such partitions as have been described are shown. The block 4^a is shown in central vertical longitudinal section. The block 4^b is shown in the same manner while the block 4^c is shown in transverse section. This view illustrates the manner in which three blocks of two different courses may cooperate to form a corner tie of the walls of a building, this being made possible by the symmetrical shaping of the male and female molding portions of the partition. In other words, by duplicating the transverse section of the partition in the formation of its longitudinal section, the male and

female portions of the resulting block will naturally be symmetrical so that the blocks of adjacent courses can cooperate with one another either in parallel half lapped relation or in half lapped relation at right angles to one another. This is important from a building standpoint since the block becomes a standard unit either in a running course or at the junction of two walls or at corners or in pilasters or in similar locations where the ends of adjacent blocks of the same course abut or are exposed.

The invention as shown in Figure 4 differs from the showing in Figures 1 and 2 only in the fact that the central portion of the partition is cut out to permit the passage of a core therethrough. Figure 5 shows the resulting cored block and it will be noted that in all respects, it is the same as the blocks shown in Figure 3 except that it is cored.

When partitions embodying the present invention are used in gang machines adapted to cast a number of blocks, a single block will be cast between each two adjacent partitions though as stated the invention is not restricted to machines of this character as it can be employed in machines of the similar type disclosed in my copending application referred to, wherein only two blocks are cast at a time, the partition serving to cast adjacent faces of the two blocks while the distant faces of the blocks are formed in the side walls of the apparatus.

In the preferred construction, the parti-

tion is twice as long as it is high, but if a longer block is desired, it may be made of a length three or more times its height by merely duplicating its cross sectional shape in the formation of its linear section. 40

The accompanying drawings show the invention in its preferred form, but it is to be understood as fully commensurate with the appended claims.

Having thus fully described the invention, 45 what I claim as new and desire to secure by Letters Patent is:

1. A mold partition, the length of which is a multiple of its height and the opposite faces of which partition are complementary 50 to one another with a linear section of the partition a duplication of the transverse section thereof.

2. A mold partition, the opposite faces of which are complementary male and female 55 and the longitudinal section of which is a duplication of its transverse section, said partition being twice as long as it is high.

3. A mold partition substantially twice as long as it is high, one face of said partition 60 being provided with projecting male portions and the opposite face of the partition being provided with complementary reentrant female portions, all of said portions being symmetrical and the longitudinal section of the partition constituting a duplication of the transverse section thereof. 65

In testimony whereof I have signed the foregoing specification.

HENRY C. NEUBERGER.
